JUDSON C. LOGAN, OF MERIDEN, CONNECTICUT, ASSIGNOR TO FOSTER, MERRIAM & COMPANY, OF MERIDEN, CONNECTICUT, A CORPORATION OF CONNECTICUT.

HANDLE FOR COOKING UTENSILS.

1,316,623.

Specification of Letters Patent. Patented Sept. 23, 1919.

Application filed February 20, 1919. Serial No. 278,278.

To all whom it may concern:

Be it known that I, JUDSON C. LOGAN, a citizen of the United States, residing at Meriden, county of New Haven, State of Connecticut, have invented an Improvement in Handles for Cooking Utensils, of which the following is a specification.

This invention has for its object to provide a heat insulating handle adapted for use on 10 cooking utensils generally and especially adapted for use on aluminum utensils, which shall be strong and durable, will not burn at the point of connection to the utensil, and shall be relatively inexpensive to produce, 15 and cool and pleasant to handle when in use.

With these and other objects in view I have devised the novel handle for cooking utensils of which the following description in connection with the accompanying drawing 20 is a specification, reference characters being used to indicate the several parts.

Figure 1 is a perspective view of a cooking utensil with my novel handle applied thereto;

25 Fig. 2 a longitudinal section, on an enlarged scale, of the handle, and showing the mode of attachment to the handle socket on the utensil, and

Fig. 3 is a perspective view of the socket 30 bushing detached.

10 denotes a cooking utensil which is provided with a handle socket 11 having a bushing 12 cast therein. The bushing is preferably, although not necessarily, made of bronze, is internally threaded and is provided with outwardly turned spurs which are cast into the socket and lock the bushing against turning. The socket is provided at its outer end, and continuous with the bore 35 of the bushing, with an enlarged air space 13, the outer end of which is counter-sunk, as at 14. 15 denotes the hand piece which is made of wood or any suitable heat resisting material, is usually covered with heat 40 resisting paint, and is provided with a longitudinal air space 17 through which the handle bolt 16 passes. This longitudinal air space in the handle is made appreciably larger than the handle bolt leaving ample 45 space for cooling purposes surrounding the handle bolt. The inner end of the handle bolt is threaded, as at 18 to engage the bushing and the outer end thereof is provided with a ring or head 19. Between the head 50 and the outer end of the handle I place a cup

shaped collar 20 through which the handle bolt passes and the flange of which engages the outer end of the handle externally. Between the inner end of the hand piece and the handle socket I place a ring shaped 60 metallic insulator 21 which is concavo-convex in cross section. The outer end of the insulator engages a shoulder 22 at the inner end of the hand piece and the inner end of the insulator is provided with a neck 65 23 which just passes within air space 13 in the handle socket. It should be noted that owing to the counter-sink at the outer end of the handle socket the insulator contacts with the socket only at the outer knife edge of 70 the socket and at the end of air space 13. It will be noted furthermore that the engagement of the neck with the wall of air space 13 retains the insulator in a central position and that collar 20 retains the handle bolt central in air space 17. 75

In assembling, the parts are placed in the position shown and the threaded inner end of the handle bolt is turned into engagement with threaded bushing 12, thus clamping the 80 parts securely together and preventing any displacement.

Having thus described my invention, I claim:

1. A handle of the character described 85 comprising a socket having a bushing cast therein and an air space, a hand piece having a longitudinal air space continuous with the air space in the socket, a ring shaped metallic insulator between the hand piece 90 and the socket, and a handle bolt passing through said air spaces and having threaded engagement with the bushing.

2. A handle of the character described 95 comprising a socket having an air space, an insulating hand piece having a longitudinal air space continuous with the air space in the socket, a concavo-convex ring shaped insulator between the hand piece and the socket, a handle bolt passing through both 100 air spaces and having threaded engagement with the socket, and a cup shaped collar engaging the outer end of the hand piece and which is engaged by the head of the bolt to clamp the parts together and which retains the bolt central in the longitudinal air space. 105

3. A handle of the character described comprising a socket having a bushing cast therein and an air space continuous with the bore of the bushing, an insulating hand piece 110

having a longitudinal air space continuous with the air space in the socket, a ring shaped insulator between the hand piece and the socket and having a neck just passing 5 within the air space in the socket and a handle bolt passing through both air spaces and engaging the bushing.

4. A handle of the character described comprising a socket having an air space, the 10 end of the socket being counter-sunk, a hand piece having a longitudinal air space continuous with the air space in the socket, a concavo-convex ring shaped insulator between the inner end of the hand piece and 15 the outer knife edge of the socket and provided with a neck passing into the air space in the socket, and a handle bolt passing

through both air spaces and having threaded engagement with the socket.

5. A handle of the character described 20 comprising a socket having an air space, the end of the socket being counter-sunk, an insulating hand piece having a shoulder at its inner end and a longitudinal air space continuous with the air space in the socket, a 25 concavo-convex ring shaped insulator engaging the shoulder on the hand piece and the outer knife edge of the socket and having a neck passing into the air space in the socket, and a handle bolt passing through 30 both air spaces and having threaded engagement with the socket.

In testimony whereof I affix my signature.
JUDSON C. LOGAN.
